TERMINATOR

Weldon O. Hampton, Chicago, Ill., assignor to The
Delta Star Electric Company, Chicago, Ill., a
corporation of Illinois

Application February 28, 1941, Serial No. 381,010

7 Claims. (Cl. 174—75)

This invention relates to potheads or terminators and more particularly to sealed potheads and the manner of sealing the same.

A pothead or terminator is a structure used for terminating the end of an electric cable, particularly where connections are made between an underground cable and an overhead or aerial conductor. Such potheads, when used on medium or high voltages, must be maintained sealed against the entrance of air or moisture thereto and against the escape of insulating compound therefrom. Any air or moisture that may enter the pothead may result in a rapid deterioration of the insulation therein and consequent breakdown of the pothead. It is one of the objects of the present invention to provide a pothead wherein most, if not all, of the joints are soldered. It is a further object of the present invention to provide a structure wherein most, if not all, of the soldered joints can be made at the factory under factory manufacturing conditions, as distinguished from the conditions prevailing in the field where the pothead is ultimately to be located. In accordance with one of the principles of the present invention the pothead terminal to which the aerial conductor is to be connected consists of a tube into which the bared end of the cable conductor may be inserted. This tube is sealed to the end of the insulator first by a gasketed seal and then by an outer soldered joint. Under normal conditions the outer soldered joint maintains the air-tight and liquid-tight condition of the terminator. However, should that factory soldered joint fail, the seal is still maintained by the gasketed joint.

It is a still further object of the present invention to provide a pothead of the above mentioned character, having a soldered joint between the terminal and the insulator, with an expansion joint between the cable conductor and the terminal stud so that the terminal stud is not subjected to alternate push and pull as the cable conductor expands or contracts under changing thermal conditions.

It is a still further object of the present invention to provide an improved means for securing the base of the insulator to its support in a manner which will provide a liquid-tight, air-tight seal. The support or pothead base consists of a casting made preferably of aluminum. A thin copper tube is embedded in the cast aluminum and extends outwardly therefrom. This tube is embedded in the aluminum during the initial casting of the aluminum case by positioning the tube in the mold and pouring the molten

aluminum around the tube. The aluminum has a higher thermal coefficient of expansion and contraction than does the copper tube. Therefore, as the aluminum solidifies it shrinks tightly around the tube and thus forms a liquid-tight, air-tight seal between the tube and the aluminum casting. The copper tube is quite thin and yielding. The lower end of the pothead insulator has a skirt that fits very loosely into the copper tube, the space between the skirt and the tube being then filled with solder and a wiped soldered joint made between the outside of the tube and the insulator. The opposite end of the mounting case may have a similar copper tube similarly mounted therein and shaped for receiving a lead sheathed cable to which a wiped joint may be made.

It is a still further object of the present invention to provide an improved insulator and terminal stud assembly such as is adapted for potheads, transformer bushings, circuit breaker bushings, or the like, and which will be free of any air spaces in regions where an electrostatic field may be set up. This is particularly important in high voltage structures, since an air space which is subject to ionization or electric discharge causes considerable interference with radio reception. By providing a construction wherein the air spaces are reduced to a minimum and, where they do exist, are not subjected to electric stress, I eliminate the electrostatic discharges and ionization which is a source of radio interference.

The attainment of the above and further objects of the present invention will be apparent from the following specification taken in conjunction with the accompanying drawing forming a part thereof.

In the drawing:

Figure 1 is an elevational view, in partial section, of a single conductor pothead constructed in accordance with the present invention;

Figure 2 is an enlarged view of a portion of the pothead of Figure 1;

Figure 3 is an elevational view of a three conductor pothead embodying the present invention;

Figure 4 is an end view of the pothead of Figure 3;

Figure 5 is an enlarged fragmentary sectional view taken along the line 5—5 of Figure 3;

Figure 6 is an elevational view, in partial section, showing a modified construction; and

Figure 7 is a fragmentary sectional view illustrating another type of mounting for the porcelain insulator.

Reference may now be had more particularly to the construction illustrated in Figures 1 and 2. The pothead includes a mounting casing 1 having integrally formed apertured mounting ears, or other mounting means, for mounting the pothead on a stationary structure. A tubular pot casing 2 extends from the bottom of the mounting casing 1 and is tapered at its lower end 3 for facilitating the making of a solder joint 4 between the pot casing and the outer lead sheath of a sheathed cable 5. A circular tube 6 extends upwardly from the top of the mounting casing 1. The tube 6 and the pot casing 2 are, preferably, thin spun copper tubes, cadmium plated. The lower end of the tube 6 is spun inwardly to form an inwardly extending lip 7 around the periphery of the tube. The edge of the lip is rounded along smooth curves so that there are no sharp corners. The mounting casing 1 is, preferably, an aluminum alloy, the preferred composition being,

	Per cent
Silicon	.25
Manganese	.50
Iron	.60
Magnesium	3.75-4
Aluminum	¹ 94-95

¹ Remainder.

The casing 1 is shrunk around the tubes 2 and 6. To accomplish this result the tubes 2 and 6 are mounted in the mold wherein the mounting casing 1 is poured so that the aluminum alloy being poured comes into contact with the tube 2 and the tube 6. The material of the mounting casing has a higher thermal coefficient of expansion and contraction than do the copper tubes 2 and 6 so that upon cooling of the cast metal of the mounting casing 1, in the mold, the aluminum alloy shrinks tightly around the tubes 2 and 6 whereby the tubes are firmly secured within the casing 1 to make a liquid-tight, air-tight seal between the tubes and the mounting casing. If desired, the tubes 2 and 6 may constitute one continuous tube.

A pothead insulator 8, preferably of wet process porcelain, has a cylindrical skirt 9 at the bottom thereof which extends into the tube 6. Before the insulator is mounted in the tube 6 a terminal stud is to be assembled at the other end of the insulator. The terminal stud extends through an opening in the insulator. It is desirable that it make a snug fit in the bore through which it extends. In molding insulators of this type it is exceedingly difficult to maintain a high degree of precision in the diameter of the hole. Usually there is a wide variation in the hole diameters in different insulators. To overcome this difficulty it has heretofore been proposed to make the diameter of the hole in the insulator undersized and enlarge it to the exact diameter required by reaming or the like. This is an expensive operation. To overcome this difficulty the bore or hole in the insulator is intentionally made oversized. It is then mounted in a mold or die and a ring 10 of lead or other suitable soft bearing metal is cast in the interior of the bore of the insulator. The molded insulator is initially provided with a peripheral notch 10' in the bore thereof, which is filled by the cast metal 10 to key the ring 10 in place. The metal ring 10 is cast to exactly the requisite diameter for making a snug fit with the terminal stud to be thereafter inserted through the ring. The ring 10 terminates flush with the adjacent top sur-

face of the insulator at the bore thereof, to constitute a seat at the inner peripheries of the gasket to be used, as will be presently explained.

At its lower end the cast metal ring 10 extends along the inner surface of the top of the insulator and continues downwardly along the peripheral wall of the insulator, as indicated at 10b. The lower edge of the metal 10b is smoothly curved to be free of any sharp corners. The portion 10b is cast integrally with the ring 10 so that there is no possible air space between the metal portion 10b and the adjacent insulator. The purpose of this extension will be more fully explained as this description proceeds.

The terminal stud for the pothead comprises a tube 11 of reduced diameter at its lower end, indicated at 12, to form a shoulder 13. A hooded disc washer 14 is fitted over the reduced end 12 of the terminal stud tube until the shoulder 13 rests against the top of the hooded disc washer. The washer makes a sealing fit with the tube 11. This may be accomplished either by providing a shrink fit between the washer and the tube, as by heating the hooded disc washer to expand the same and then sliding it into position on the tube, or it may be brazed or soldered on the tube at the shoulder 13. Thereafter an asbestos or the like sealing gasket 15 is placed on the top of the insulator 8 and then the end 12 of the tube 11 is lowered into the top opening of the insulator, passing through the lead liner 10 with which it makes a snug fit. After the stud has been positioned on the insulator, a gasket 16, a ring 17 and a gasket 18 are strung on the lower end of the tube 11. Thereafter the lower end 12 of the stud 11 is spun outwardly to form a flange 20 to retain the stud against withdrawal. During the spinning operation the stud tube 11 is pressed firmly towards the insulator to place the gasket 15 under high compression, and the spun flange 20 is also forced towards the insulator to place the gaskets 16 and 18 under high compression. Thereafter the portion 12 of the stud 11 is permanently under tension and maintains gaskets 15, 16 and 18 under compression, thus providing a liquid-tight, air-tight seal against the entry of air or moisture into the insulator by creepage along the outer top surface of the insulator. The ring 17 prevents outward spreading of the tube 11 above the part that is to constitute the flange 20 as the tube flange is spun outwardly, so that the portion 20 forms a flange at substantially right angles to the tube.

The hooded disc washer 14 includes a downwardly extending flange 21 which loosely embraces the top of the insulator. The adjacent surface of the insulator is treated to render it receptive to solder as by forming a thin metallic glaze on the surface of the insulator. This metallic glaze is exceedingly thin and may comprise silver, platinum, or any other suitable exceedingly thin metal. Thereafter a soldered sealing joint 22 is formed around the entire periphery of the flange 21, between the flange and the metallic glaze at the top of the insulator, securing the hooded washer 14 to the insulator. This maintains a liquid-tight, air-tight seal to prevent the entrance of air or moisture by creepage along the top of the insulator. However, if the soldered joint 22 should ultimately commence to leak, the seal will still be maintained by the compression of the gaskets 15, 16 and 18.

Prior to the operation of spinning the flange 20, or after that operation, if desired, a wedge-shaped ring 24 is secured in the lower end of

the tube 12, in any convenient manner as, for instance, by brazing.

The lower end 9 of the insulator 8 is then to be mounted in the tube 6. Before the insulator is mounted in the tube, a graphited asbestos gasket 28 is positioned at the bottom of the tube 6 resting on the inturned peripherally extending lip 7. This gasket may be positioned in the tube 6 before or after the metal 1 is cast around the tube. The outer surface of the lower end 9 of the insulator is metal glazed to render it receptive to solder. This metal glaze consists of an exceedingly thin film of metal united to the glaze on the porcelain. The lower end of the insulator 9 is then inserted into the tube 6 until the insulator comes to rest upon the graphited asbestos gasket. The gasket thus serves to center the insulator in the tube 6. Thereafter liquid solder 29 is poured into the space above the gasket 28. The solder unites with the metal glaze on the insulator and with the tube 6 to form a liquid-tight, air-tight permanent seal between the tube and the insulator. To facilitate pouring of the solder the top inner edge of the tube 6 is beveled to act as a funnel. The top surface of the solder is smoothed off along a smooth curve extending between the top of the tube 6 and the metallic glazed surface of the insulator.

The structure comprising the mounting casing 1, pot casing 2, tube 6, insulator 9, solder joint 29, terminal stud 11, spun over the insulator, at 20, constitutes a factory assembled unit ready for use in the field.

When the pothead is to be used in the field it is mounted in place and the bared end of the conductor of the cable 5 is inserted through the opening at the lower end 3 of the pot casing 2 and pushed forward until the cable conductor 30 extends through and above the top of the terminal stud tube 11. At this time the cable insulation has been bared to 31, which is below the wedge-shaped ring 24. The lead sheath extends into the pot casing 2. Thereafter the wiped soldered joint 4 may be made and then the upper end of the cable conductor 30 cut off flush with the top of the terminal stud tube 11. The space between the conductor 30 and the inner periphery of the terminal stud tube 11 is then packed with silver wool or copper wool 32. The copper or silver wool is packed tight, resting on the wedge-shaped ring 24 which fits fairly snugly, but not too snugly, around the conductor 30. A second wedge-shaped ring 33, which fits snugly in the terminal stud tube 11, is then placed into the tube and around the end of the conductor 30. This ring is to be used for compressing the silver or copper wool longitudinally and thus force it into firm pressure engagement with the stranded conductor 30 and with the stud 11. The pothead is then filled with insulating oil or hot insulating compound in the usual manner, as through a pouring opening in the pot casing 2, which opening is closed by a threaded plug 34. After the pothead has been filled with the insulating compound the clamping wedge ring 33 is forced downwardly by the threaded shank 36 of a cap 37, which threaded shank threads into the threaded terminal stud tube 11. The cap is forced into the tube until its square shoulder 38 seats on the top flat surface of the tube 11. Thereafter a soldered sealing joint 39 is formed around the seating surface between the cap 37 and the terminal stud tube.

The terminal stud tube 11 is adapted to receive the lug of an aerial conductor. The aerial con-

ductor may be connected to the tube 11 in any desired well known manner. If desired a portion of the tube 11 below the top thereof may be of enlarged diameter and externally threaded to receive clamping means for clamping an aerial lug to the tube 11. However, the connection between the aerial conductor and the tube 11 is not a part of the present invention and may be made in any desired manner.

10 From the above description it is apparent that the pothead of the present invention may be installed in the field in a simple and reliable manner. Only two soldered joints need be made in the field, namely, the wiped joint 4 and the joint 39. The other soldered joints are all made in the factory.

As the pothead and the cable undergo thermal changes resulting in expansion and contraction of the cable conductor, the conductor 30 is free to slide in the pothead while maintaining firm electric contact with the silver or copper wool 32. The electrical connection between the conductor 30 and the tube 11 thus constitutes a sliding or expansion joint. As a result of this arrangement 25 the expansion or contraction of the cable does not produce an appreciable strain upon the tube 11 and the pothead. Since there are no appreciable alternating strains produced on the stud 11 by the cable conductor, the gaskets 15, 16 and 18, and the wiped joint 22, are therefore not as likely to develop leaks as would be the case if the stud 11 were subjected to alternate substantial push and pull by the conductor. Should the soldered joint 22 develop a leak the gaskets 15, 30 16 and 18, being maintained under compression by the flange 20, would prevent leakage of air or moisture into the pothead.

When the pothead is filled with insulating compound it is not possible to vent the space above 40 the flange 20. The metal portion 10b is provided to prevent ionization or corona discharge in said space, since the metal portion 10b is at exactly the same potential as is the terminal stud 11. There can be no corona discharge in the air 45 space between the metal portion 10b and the flange 20 or the ring 17. This substantially reduces any radio interference. Furthermore, even aside from radio interference, corona discharge is productive of ozone which rapidly deteriorates 50 the gasket material. By providing the shielding portion 10b, which prevents corona discharge, I thereby eliminate the possibility of production of ozone in the adjacent air space and consequent rapid deterioration of the gasket material. While 55 I have shown the metal portion 10b as part of the cast metal ring 10, this portion may, if desired, consist of a thin metallic glaze or film formed on the corresponding part of the insulator and in electric connection with the bottom of the ring 10 and, therefore, in electrical connection with the terminal 11. It is also to be noted that the solder at 22 is curved along a smooth curve and that the hooded disc 21 is also free of sharp corners. This eliminates the formation of streamers or electric discharge at the top of the insulator. If any air becomes trapped between the bottom 9 of the insulator and the tube 6 this can be of no 60 harmful consequence since here again opposite sides of the air space would be at the same electric potential and therefore there would be no possibility for streamer or corona discharge through such air space.

In Figures 3 through 5 I have shown the present invention applied to a three conductor pothead. 75 This pothead includes an inverted, almost coni-

cal housing 45 and a cover 46 both made, preferably, of an aluminum alloy such as the alloy of the mounting casing 1. The housing 45 may have mounting ears or other mounting means cast integrally therewith or may be mounted in place in any desired manner. The pot casing 2' is of a construction the same as the pot casing 2 and adapted to receive a three conductor lead sheath cable 5' with which a wiped soldered joint 4' is made. The housing 45 is shrunk about the pot casing 2' by casting the metal of the housing 45 around the tube 2' which is placed in the mold previous to the casting operation, the same as the casing 2 is placed in the mold preparatory to the casting of the mounting casing 1.

The housing 45 has a flat upper seating surface 47 for receiving the cover 46, a sealing gasket 48 being interposed between the cover and the housing. The cast housing 45 is provided with indentations 49 for receiving bolts 50 that thread into tapped holes in a thickened portion 51 at the base of the cover 46. The bolts 50 are drawn exceedingly tight to secure the cover to the housing 45 and compress the gasket 48 sufficiently to maintain a liquid-tight, air-tight seal.

The cover 46 has a number of tubes 6', in this instance three, of copper or the like, identical with the tubes 6 of Figure 1, formed therein. The metal of the cover 46 is shrunk around the tubes 6' during the casting operation, the tubes being mounted in the mold and the metal of the cover 46 cast around the tubes in the same manner as the mounting casing 1 of Figure 1 is cast around the tube 6. Three insulators 8, of the same construction as the insulator of Figure 1, extend into the tube 6 and are soldered thereto in the same manner as is illustrated in Figure 1. The insulator 8 of Figure 3 is of the same construction as the insulator of Figure 1 and has a terminal stud tube 11 of the same construction and assembled together in the same manner as in Figure 1. Insofar as these constructions are identical, similar reference numerals have been used and a repetition of the description is unnecessary at this point.

The cover 46 with the three insulators 8 mounted thereon each by a soldered joint 29 and each having a tubular terminal 11 secured in place at its opposite end, as illustrated in Figure 1, constitutes a factory assembled unit. When the pothead is to be used the end of the cable is stripped of its sheath and the three conductors of the cable are fanned out, and the ends of the conductors bared of insulation the same as in Figure 1. The end of the conductor is inserted through the housing 45 and the three ends of the conductors are passed through the respective insulators and through the respective terminal tubes 11 until the ends of the conductors extend above the terminal tubes 11. Then the cover is tightly bolted to the casing 45. Thereafter the ends of the conductors are cut off flush with the tops of the tubes 11 and the electrical connections completed in the same manner as was previously described in connection with the pothead of Figure 1, and the pothead is then filled with insulating oil or insulating compound.

Reference may now be had more particularly to Figure 6 wherein there is illustrated a modified form of joint between the cable conductor and the tube 11. In this construction the bared end of the cable conductor, indicated at 60, has an expansion joint 61 secured thereto, which expansion joint includes a conductor rod 63. The conductor rod 63 extends through the tube 11 75 space. The lower end of the tube 6 is curved

in the same manner as the conductor 30 of the pothead previously described extends through the tube. In this construction the wedge-shaped ring 24 is located appreciably higher than in the construction previously described, but is otherwise of the same construction. Before insertion of the conductor through the insulator 8 the conductor 63 is wrapped with a number of turns 64 of asbestos thread to form a temporary seal between the conductor 63 and the ring 24. Thereafter the electrical connection between the conductor 63 and the tube 11 is effected by pouring hot solder 67 into the tube. Upon solidification the solder maintains the electrical connection between the conductor 63 and the tube. The expansion joint 61 is preferably of a construction such as is illustrated in Figure 4 of my co-pending application, Serial No. 375,135, to which reference may be had for a more complete description of this expansion joint. However, it is sufficient for this purpose to state that the expansion joint consists of a conducting lug 70 bolted or otherwise secured in conducting relationship to the end of the cable conductor 60, which lug 70 has a flange 71 slotted for receiving flexible laminated conductors 72, the opposite ends of which extend into slots in a flange 73 similar to the flange 71, which flange has a conductor stud 63 extending therefrom as an integral part thereof instead of being bolted thereto as the cable conductor is bolted to the lug 70. As the cable conductor expands or contracts the lug 70 moves towards or away from the lug 74 but does not exert any appreciable push or pull on the lug 74, since the flexible laminations 72 bow to permit the flanges 71-73 to approach or recede from one another. In this construction the mounting casing 1 is made in two ring parts, bolted together in the same manner as are the parts 45-46 of the pot-head of Figure 3, with a suitable sealing gasket, such as the gasket 48, interposed. It is, however, to be understood that any other means may be provided for bolting a pot casing 2 to a mounting casing or mounting flange that is cast around the tube 6. A bolted connection is used in order to permit positioning of the expansion joint in the insulator. A suitable type of bolted connection between the casing 1 that is molded around the tube 6 of the pothead of Figure 6 and the pot casing 2 is shown in my pending application previously referred to, to which reference may be had.

Figure 7 shows an alternate means for securing the insulator in the tube 6. In this construction the lower end of the skirt 9 of the insulator is of slightly reduced diameter, as indicated at 80. This portion 80 together with the adjacent portion 81 of the insulator is metal glazed in the same manner as was previously described. A wrapping of asbestos thread 82 is wrapped around the lower part of the insulator. Thereafter the insulator is inserted into the tube 6. The thread 82 is compressed by the tube and thus forms a temporary seal or stop for the filling of solder 29, which is thereafter poured into the space between the insulator and the tube 6. The solder unites the tube 6 with the metal glaze on the insulator 9. The space between the part 80 of the insulator and the tube 6 will necessarily contain some air. This air is, however, free of any electric potential difference since the metal glaze at 80 is at the same potential as is the adjacent surface of the tube 6. There is thus no possibility of corona or streamer formation in this air space. The lower end of the tube 6 is curved

along a smooth curve, as indicated at 84, to avoid any sharp corners and corresponding concentration of electric stresses at such places. It is thus apparent that when the insulator is mounted in its tube in the manner illustrated in Figure 7, there is no possibility of corona discharge.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. In combination, a hollow insulator having a stud receiving opening, a metal member overlying the insulator and surrounding the opening, a tubular stud extending through the member into the insulator and having a shoulder bearing against the outer side of the member, and a sealing joint between the member and the shoulder, the inner end of the stud being flared and held by the inner side of the insulator to secure the stud against retraction from the insulator.

2. In combination, a hollow insulator having a stud receiving opening, a metal member overlying the insulator and surrounding the opening, a tubular stud extending through the member into the insulator and bearing against the outer side of the member, the inner end of the stud being flared to a diameter greater than that of the insulator opening to secure the stud against retraction from the insulator, and a soldered sealing connection between the metal member and the insulator.

3. Electric apparatus comprising a hollow insulator having an opening therein, a terminal stud extending into said opening, a metal disc surrounding and making a shrunk sealing fit around the stud on the outside of the insulator, said stud having an outward projection on the part thereof inside of the insulator, and means cooperating with said projection for holding the stud against retraction from within the insulator, and a fused metal sealing joint between the outer periphery of the disc and the insulator.

4. Electrical apparatus comprising a hollow insulator open at both ends, a hollow terminal stud closing one end of the insulator, a metallic seal joining the stud to the insulator and fused to the insulator, a cable conductor extending into the insulator at the opposite end thereof and secured thereto and subject to alternate forces tending to move the cable conductor longitudinally in the insulator, electric connecting means between the conductor and interior of the terminal stud, said connecting means including an expansion joint for taking up expansion and contraction of the conductor and thus preventing the forces on the cable from producing alternate

stresses in the fused metal joint, and means at that end of the stud which is on the outside of the insulator for obtaining access to the interior of the hollow stud to facilitate making of the electric connections between the stud and the cable conductor.

5. A pothead comprising a hollow insulator, a tubular terminal extending through the insulator at one end thereof and sealed thereto by a fused metal seal, a conductor extending through the insulator from the opposite end thereof and into the tubular terminal, and a filling of compacted conducting filaments between the conductor and the inside of the terminal, said conductor being longitudinally slidable in said filling, and means operable from outside of the pothead for maintaining said filling material under axial compression to expand the same radially into pressure contact with the conductor and with the tubular terminal.

15 6. Electric apparatus including a tubular terminal stud, a disc through which the stud extends, said disc making a sealing fit with the stud, a supporting structure for the stud and disc, 20 a fused metallic seal between the outer periphery of the disc and the supporting structure, a conductor terminating in the stud and subject to alternate forces tending to move it lengthwise of the stud, a filling of compacted conducting filaments between the conductor and the stud for maintaining electrical connections between the two while permitting relative movement thereby preventing transmission of said alternate forces from the conductor through the stud and disc to the metallic seal between the disc and the support, and means operable from the side of the stud on the outside of the structure for compacting the conducting filaments.

25 7. Electric apparatus including a conducting 30 tube open at both ends, a stationary support upon which the tube is immovably mounted, a cable conductor the end of which extends into one end of the tube and terminates in the tube and is of substantially smaller effective outside diameter than the inside diameter of the tube, a packed mass of intertwined conducting metallic filaments in the space between the conductor and the tube and means operable from the opposite open end of the tube for compressing the conducting filaments axially to force them into pressure contact with the tube and with the conductor, said conductor and tube being relatively slidable while both are in pressure engagement with the conducting filament packing whereby thermal expansion and contraction of the cable conductor results in sliding of the end of the cable in the tube while the tube remains stationary on the support.
